TRAIN DISPATCHING SYSTEM FOR
RAILROADS

Oscar H. Dicke, Rochester, N. Y., assignor to General Railway Signal Company, Rochester, N. Y.

Application May 24, 1929, Serial No. 365,641

25 Claims. (Cl. 246—3)

This invention relates to train dispatching systems, and more particularly to a train dispatching system of the synchronous selector type including synchronous apparatus for selecting way stations and synchronous apparatus for selecting specific message circuit branches at such way stations.

In the provision of train dispatching apparatus, not only is it necessary to control distant traffic controlling devices, but it is essential to indicate in the dispatcher's office how trains are progressing, by repeating in the dispatcher's office the condition of track relays associated with various track sections along the railway track, and further it is also important for the dispatcher to know the indicating conditions of wayside signals and the positions of track switches in the territory under his control. In certain systems there are substantially as many distinctive controls to be transmitted to a particular way station as there are number of indicating conditions that must be transmitted to the dispatcher's office, and the present invention is particularly well adapted to a system of this kind, for reasons pointed out hereinafter. Also, since the various wayside signals and switch machines are controlled from a central point, namely the dispatcher's office, but whereas the indications of train progress, indicating conditions of signals and positions of switch machines originate at a large number of distributed way stations, it becomes apparent that the rapidity of indicating OS-ing functions of a train dispatching system are much more essential than are the rapidity with which controlling functions are carried out. In other words, the various controlling conditions originate with the dispatcher himself and therefore can never be a surprise to him, whereas the indicating conditions originate at distant points and are transmitted automatically and are in the nature of a surprise to the dispatcher. In order to inform the dispatcher as quickly as possible of certain changes in traffic conditions, the feature of transmitting OS indications should have preference over the control features of the system, and should not be delayed more than absolutely necessary. The dispatching system embodying the present invention is so organized that under normal conditions, that is, when the dispatcher has not recently moved a lever, the synchronous selector system scans, so to speak, the conditions of the various track relays, switch machine positions, and signal indicating conditions, so that no time is lost in properly informing the dispatcher of conditions of traffic on the railway system.

More specifically, the present invention resides in a double synchronous selector system one branch of which is controlled by polar direct current relays, and the other branch of which is controlled by alternating current relays connected in multiple with said direct current relays. Each alternating current relay controls a series of stepping relays for selecting the way stations, whereas the direct current polar line relay at each way station controls a series of stepping relays only when such way station is selected, and each of these stepping relays is adapted to transmit a certain indication to the dispatcher's office. Also, distinctive controls are transmitted to a particular selected way station, if a particular OS-ing channel circuit is completed for more than a predetermined period of time. In other words, the message circuits, whereby indications are transmitted from the way station to the dispatcher's office are not used for the purpose of transmitting a control to the distant way station, but this control is transmitted by the fact that a particular channel selecting relay is energized for a longer time than it would be if such control were not to be transmitted. Putting it briefly, the system embodying the present invention resides in an OS scanning synchronous selector system, in which, if a particular OS channel is completed for more than the usual stepping time, the energization of a slow-acting relay is effected, which completes a local circuit carrying through a front contact of such slow-acting relay and the front contact of the channel selecting relay, the completion of which local circuit sets up a control condition at such way station which will remain in effect, until cancelled by a conflicting control condition.

Other features of the present invention reside in the provision of a series of stepping relays in the dispatcher's office, used not only for controlling the polar stepping relays distributed along the railway system one at each way station, but also used for controlling the alternating current line relays, which in turn control stepping relays for selecting way stations, and are still further so organized that upon movement of a lever by the dispatcher, a hesitation is caused to occur at a particular step in the stepping sequence, thereby causing a certain control function to occur. Another feature of the present invention resides in a circuit arrangement whereby the combination of lever positions determines the character of the control to be transmitted to the corresponding distant way station.

tures of the present invention will in part be apparent from the accompanying drawings and in part be pointed out in the description herein-after.

5 In describing the invention in detail, reference will be made to the accompanying drawings, in which:—

10 Figs. 1A and 1B when laid end to end show the dispatcher's office equipment of one embodiment 10 of the present invention in a conventional manner; and

15 Fig. 1C illustrates conventionally the apparatus at one way station, together with the line 15 relays, hesitating relay, and reset relay of another way station.

20 *Structure.*—Referring to Fig. 1C of the drawings, the present invention has been shown applied to a single track railway system, preferably equipped with absolute-permissive-block signaling; and which railway system includes a plurality of passing sidings, with each passing siding having its track switches preferably operated by switch machines and having each end thereof 25 of preferably provided with the usual stop-and-stay starting and entering signals.

25 For convenience and for the purpose of simplification only a single passing siding PS has been illustrated. At the east end of this passing siding are provided a main starting signal S², a dwarf starting signal S⁴ for controlling the movement of trains off of the main track and siding respectively, a main entering signal S¹ and a take-siding signal S³ for governing the movement of trains into the main track and siding, respectively, 30 the switch at this east end of the siding being controlled by the switch machine SM. This track switch at the east end of passing siding PS has associated with it the usual detector track circuit including the detector track relay DT and a track battery 10. Similarly, the condition of the occupancy of the main track of the passing siding is manifested by a track relay T of the usual normally closed type track circuit including the track 35 battery 11.

40 45 In order to aid the dispatcher in observing the progress of trains on the system, there is provided in the dispatcher's office a miniature track layout reproducing in every detail the layout of the railway system over which he has control, and of which the miniature passing siding ps for convenience only has been illustrated (see Fig. 1A). Associated with the east end of this miniature passing siding ps is a switch machine lever SML and a signal control lever SCL, and suitable 50 indicating lamps, or other indicators, for indicating the position of the switch machine, indicating the condition of the signals, and indicating the occupancy of the detector track circuit and the track circuit for the main track of the passing siding.

55 60 The indicating lamp DL when illuminated indicated the occupancy of the detector track circuit at way station No. 2 (see Fig. 1C), while the lamp TL indicates the occupancy of the main track of the passing siding when illuminated. The lamps RL and NL indicate when illuminated, respectively, the reverse and normal position of the switch machine SM. Indicating lamp EL indicates that an east bound signal is at proceed, the lamp WL indicates that a west bound signal is at proceed and the lamp SL indicated that all of the signals are at stop.

65 70 75 Referring again to Fig. 1C of the drawings the wayside signals S¹, S², S³ and S⁴ and the switch machine SM at way station No. 2 are controlled

by the four polar permanent magnet stick relays EM, ES, WM and WS. The reference characters of these relays indicate their functions as follows:—relay EM when energized to the right sets up east bound traffic on the main track, relay WM to the right sets up west bound traffic on the main track, relay ES to the right sets up east bound traffic on the siding, and relay WS to the right sets up west bound traffic on the siding, these relays being so controlled that only one of these relays assumes the right hand position at one time. These relays EM, WM, ES and WS are controlled by the neutral relays CA², CB², CC², CD² and relay ST², in a manner as more particularly described hereinafter.

5

15

20

25

The stepping line extends throughout the entire railway system, and at each way station includes in series therewith one of the direct current polar relays LR⁰, LR¹, LR², etc., each way station direct current polar line relay having in 20 multiple therewith an alternating current transfer line relay TR having a corresponding exponent. If desired, however, two separate line wires may be used one containing the direct current relays and the other containing the alternating current relays in series.

25 For the way station No. 1 there have been illustrated only the line relays LR¹ and TR¹, and the slow-acting relays HR¹ and RSR¹ controlled by the line relay LR¹. For the way station No. 2, 30 however, have been illustrated a series of station selecting stepping relays SR¹, SR², SR³, etc. which are controlled by the alternating current transfer relay TR², these station selecting relays rendering effective the direct current polar line 35 relay of the particular station that has been selected, so that such direct current polar relay may control the channel selecting relays of that particular way station. For way station No. 2 these channel selecting relays have been designated A², B², C², D² and E², and these channel selecting relays for way station No. 2 can be controlled only by the line relay LR² when the station selecting relay SR² is energized, all in a manner as pointed out in the operation herein- 40 after.

45

45 Each way station is also provided with a slow-acting hesitating relay, which hesitating relay HR² for way station No. 2 through the medium of a particular channel selecting relay A², B², etc. 50 may control a particular control relay such as CA², CB², CC², CD² and ST², when the system hesitates during the step when a particular channel selecting relay is energized.

55

55 Each way station is also provided with a reset relay designated RSR¹, RSR², etc. which reset relays assure that all of the way station selecting relays SR¹, SR², SR³, etc. and all of the channel selecting relays A, B, C, D and E, each having a proper distinctive exponent corresponding to the 60 way station, have assumed their de-energized condition when the system begins a new cycle of operation.

65

65 In the dispatcher's office (see Figs. 1A and 1B) there are provided a series of stepping relays 1A, 1B, 1C, 1D, 1E, 2A, 2B, 2C, 2D, 2E, 3A, 3B, 3C, 3D, 3E, etc. which stepping relays are connected in a circuit arrangement to be successively energized and in turn repeatedly change the polarity of current applied to the stepping line 70 and also apply alternating current to this stepping line 1 at intervals and during a predetermined number of steps of application of direct current to this stepping line 1. Further, in order to cause particular relays in this series of stepping 75

5 relays to be energized longer than others, that is, to cause them to hesitate, there have been provided control relays CA⁰, CB⁰, CC⁰, CD⁰, and ST⁰, each having associated therewith a slow-
acting relay, which slow-acting hesitating relays are designated respectively HA, HB, HC, HD, and HS.

10 The alternating current heretofore mentioned as being applied to the stepping line 1, is derived from a high frequency generator HFG having connected in series therewith a condenser 13, which condenser prevents the flow of direct current through this generator HFG. The indicating lamps shown in the dispatcher's office and 15 heretofore described are controlled by indicating relays designated SI, TI, DI, EW, and SMI, the functions of which will be described more particularly hereinafter.

20 In Fig. 1A of the drawings, there has been shown a battery 25, having its midpoint connected to the common return wire C through a knife switch 26. The two extreme terminals of this battery 25 have been designated (B+) and (B-), which furnish positive and negative 25 potential respectively, with respect to said common wire C. It will be noted that certain of the wires in Figs. 1A and 1B terminate at points similarly designated as (B+) and (B-), which are understood to be the terminals of battery 25. 30 Also, certain other points in the Figs. 1A and 1B designated as B are to have a suitable positive potential from a suitable battery applied to these points with respect to the common wire C. It will be further noted that the points in Fig. 1C which 35 are designated (B+) and (B-), are furnished with positive or negative potential in respect to the common wire C from some suitable source located at that particular station, while the points marked B receive positive potential from the 40 same or some other suitable source with respect to the common wire C.

45 It will be noted here that the switch 26 is used to stop the system for repairs or other suitable reasons, and has been shown open in this specific case.

Having made brief reference to the various structural features, it is considered expedient to now take up the operation of the system in order to 50 get a complete understanding of the nature and operating characteristics of the invention.

Operation

55 The dispatching system shown as an embodiment of the present invention, is normally in operation for OS scanning. In other words, the system normally operates to select each way station in proper sequence, and while having a particular way station selected, a plurality of message channels are set up, over which OS indications, or other indications, may be transmitted to the dispatcher's office.

60 The various traffic controlling devices according to this invention are governed collectively according to the route over which it is desired to have a particular train pass, rather than controlling each individual traffic controlling device separately. Also, rather than transmitting a distinctive impulse through a message channel from the dispatcher's office to a particular way station for controlling the traffic controlling devices, this 65 invention sets forth a means whereby local circuits are completed, which may be conveniently termed local hesitation repeater circuits, as these 70 circuits are due to the repetition of hesitation

caused in the dispatcher's office as a result of the movement of certain control levers.

75 As these several operations or functions of the system are distinctive within themselves, particular attention will be directed to the discussion 5 concerning each operation separately as well as their co-relation with each other.

Sequential operation.—To facilitate description of the system, the switch 26 has been shown open so that the various relays will be at rest, 10 which relays for convenience have been shown as if they had just completed a cycle of operation.

Let us now assume, that the switch 26 is closed 15 to render the battery 25 available for the application of current to the stepping wire 1.

The closure of switch 26 applies current of negative polarity to the stepping line 1 and causes the line relays LR⁰, LR¹, and LR² to be operated to the left through the following circuit:—beginning at the terminal (B-), back contact 20 of relay 3E, back contacts 21, 22, 23, 24, 25, 26, 27, 28, 29, 30, 31, 32, 33, and 34 of the various stepping relays in the dispatcher's office, inductive reactance 35, which chokes back the flow of 25 high frequency alternating current therethrough, line relay LR⁰, stepping line 1 between the dispatcher's office and way station No. 1 line relay LR¹, stepping line between way station No. 1 and way station No. 2 line relay LR², to common 30 return wire C connected through the switch 26 to the battery 25. The completion of this circuit causes the line relays LR⁰, LR¹, LR², to be operated to their left hand positions, but since none of the station selecting relays SR¹, SR², 35 SR³ are now in their energized condition no particular function will be carried out at any of the way stations at this time in response to this change in the position of the line relays LR² and LR³. Movement of the line relay LR⁰, to the left 40 however, will complete the following energizing circuit for the stepping relay 1A:—beginning at the terminal B of a suitable battery, contact 37 of line relay LR⁰ in its left hand position, wires 38 and 39, back contact 85, wires 40 and 41, 45 winding of the relay 1A, wire 42, back contact 43 of relay 1B, wires 44 and 45, back contact 46 of relay 1C, wires 47 and 48, back contact 49 of relay 1D, wires 50 and 51, back contact 52 of relay 1E, wires 53 and 54, back contact 55 of relay 50 2A, wires 56 and 57, back contact 58 of relay 2B, wires 59 and 60, back contact 61 of relay 2C, wires 62 and 63, back contact 64 of relay 2D, wires 65 and 66, back contact 67 of relay 2E, wires 68 and 69, back contact 70 of relay 3A, wires 71 and 72, 55 back contacts 73 of relay 3B, wires 74 and 75, back contact 76 of relay 3C, wires 77 and 78, back contact 79 of relay 3D, wires 80 and 81, and back contact 82 of the relay 3E, to the common return wire C connected to the other terminal of the 60 battery. The completion of this circuit effects energization of the relay 1A, thereby causing the following stick circuit to be closed:—beginning at the terminal B of the same battery, front stick contact 83 of the relay 1A, wires 84 and 41, winding of the relay 1A, and the elements 42 to 32 inclusive of the circuit just traced, so that the relay 1A remains stuck up until this stick circuit is 65 broken.

Having now explained how movement of the 70 line relay LR⁰ from its right hand position to its left hand position has picked up the relay 1A, attention is directed to the fact that similar movement of the line relay LR² to its left hand position causes reversal of the polarity applied 75

to the reset relay RSR^2 , so that this relay RSR^2 assumes its deenergized position.

- It will be noted here, that the contacts of relays RSR^1 , RSR^2 and etc. are slow to pick-up, requiring a time which is greater than the pick-up time of the relays HR^1 , HR^2 etc. It will also be noted that the pick-up time of the relays HR^1 and HR^2 is equal to the pick-up time of the relays HA , HB and HD , or in other words the relays HA , HB and HD determine the period of time during which the relays HR^1 and HR^2 pick up. However, this period of time as determined by the relays HA , HB and HD is not sufficiently long enough to pick up the contacts of relays RSR^1 and RSR^2 , which pick-up time for said re-set relays RSR^1 and RSR^2 is determined by the period of time during which the contacts of relay $3E$ are assuming an energized position. Hence, it is seen that under normal operation, the contacts of the reset relays RSR^1 , RSR^2 , etc. are caused to assume deenergized positions by a positive impulse placed upon them, as a result of the energization of relay $3E$, after the long negative impulse placed on the stepping line by relay $3D$ due to relay $3E$ having a slow pick-up period. Thus, the SR^1 relay at each station is energized before the negative impulse is placed upon the stepping line for energizing relays $1A$ and A^1 .
- With the relays RSR^1 and RSR^2 and all other reset relays deenergized, circuits are completed at the respective way stations through which the SR^1 relay at each way station may be energized.

With the relay RSR^2 deenergized a circuit is closed for energizing the station selecting relay SR^1 , which may be traced as follows:—beginning at the terminal B of a suitable battery (see Fig. 1C) back contact 90 of the alternating current transfer relay TR^2 , wires 91 and 286 , back contact 92 , wire 93 , winding of the relay SR^1 , wire 94 , back contact 95 of the relay SR^2 , wires 96 and 97 , back contact 98 of the relay SR^3 , wires 99 , 100 and 101 , back contact 102 of the relay RSR^2 to the common return wire C connected to the opposite terminal of said battery. It is thus seen, that at station No. 1 the first channel selecting relay A^1 (not shown) may be picked up at said way station, all in a manner as more clearly explained in connection with station No. 2 hereinafter.

With the relay $1A$ now energized current of positive polarity is applied to the line circuit as follows:—beginning at the terminal ($B+$) of battery 25 , through front contact 36 of the relay $1A$, choke or inductive reactance 35 , line relay LR^0 , line wire 1 , line relay LR^1 , wire 1 , line relay LR^2 to common return wire C , back to the mid point of battery 25 . The application of this current moves the contacts of relays LR^0 , LR^1 and LR^2 to the right, but this operation of the line relay LR^2 accomplishes no result because the station selecting relay SR^2 is still deenergized. Operation of the line relay LR^1 , however, effects energization of a channel selecting relay, not shown, and therefore its operation can not be conveniently pointed out.

Operation of the line relay LR^0 to the right, causes the relay $1B$ to be energized through the following circuit:—beginning at the terminal B , contact 37 of the relay LR^0 to the right, wires 105 , 120 , and 106 , front contact 107 of the relay $1A$, wires 108 and 109 , winding of the relay $1B$, wires 110 and 45 , and then through elements 46 to 82 inclusive, (see Figs. 1A and 1B) to common return wire C . With the contacts of relay $1B$

picked up, the following stick circuit for relay $1B$ is closed:—beginning at the terminal B , front contacts 111 of the relay $1B$, wires 112 and 103 , winding of the relay $1B$, wires 110 and 45 , and then through elements 46 to 82 , inclusive, to common return wire C . Picking up of the contact 85 of relay $1B$ opens the energizing circuit of relay $1A$, so that current cannot be fed back through stick contact 83 of relay $1A$ to the wires 38 and 39 , and also the picking up of contact 43 of this relay $1B$ breaks the stick circuit for the relay $1A$, so that the relay $1A$ is deenergized. Also, with the contacts of relay $1B$ picked up, negative potential is applied to the line relays LR^0 , LR^1 and LR^2 through front contact 33 of relay $1B$ and back contact 34 of relay $1A$, (this relay $1A$ having been dropped by the opening of contact 43 of relay $1B$), so that these line relays LR^0 , LR^1 and LR^2 are energized to the left.

With the line relay LR^0 energized to the left the following pick-up circuit for the relay $1C$ is closed:—beginning at the terminal B , contact 37 to the left, wires 38 and 39 , front contact 85 of relay $1B$, wires 114 and 115 , winding of the relay $1C$, wires 116 and 48 , through the elements 49 to 82 , inclusive, (see Figs. 1A and 1B), to common return wire C , connected to the other terminal of said battery. With the relay $1C$ energized the following stick circuit for this relay is closed:—beginning at the terminal B , front stick contact 117 of the relay $1C$, wires 118 and 115 , winding of the relay $1C$, wires 116 and 48 , and then through elements 49 to 82 , inclusive, to common return wire C .

With the contacts of relay $1C$ assuming their energized positions, positive potential is applied to the line relays LR^0 , LR^1 and LR^2 through front contact 32 of relay $1C$ and back contacts 33 and 34 of relays $1B$ and $1A$, the relay $1B$ having assumed its deenergized position in response to opening of its stick circuit at contact 46 of relay $1C$. With the contacts of the line relays LR^0 , LR^1 and LR^2 assuming their right hand position in response to this energization of relay $1C$, a pick-up circuit for the relay $1D$ is completed which may be traced as follows:—beginning at the terminal B , contact 37 of the relay LR^0 assuming its right hand position, wires 105 , 120 and 121 , front contact 122 of relay $1C$, wires 123 and 124 , winding of the relay $1D$, wires 125 and 51 , and then through elements 52 to 82 inclusive to common return wire C . With the relay $1D$ energized, the following stick circuit for this relay is closed:—beginning at the terminal B , front contact 126 of the relay $1D$, wires 127 and 124 , winding of the relay $1D$, wires 125 and 51 , and then through elements 52 to 82 , inclusive, to common return wire C .

With the relay $1D$ energized opening of its contact 49 deenergizes the stepping relay $1C$, thereby closing a circuit for energizing the line relays LR^0 , LR^1 and LR^2 with current of negative polarity, through the medium of front contact 31 of relay $1D$ and back contacts 32 and 33 and 34 of the relays $1C$, $1B$ and $1A$, respectively.

With the contacts of the relay LR^0 now assuming left hand positions the relay $1E$ is energized through the following circuit:—beginning at the terminal B , contact 37 of relay LR^0 to the left, wires 38 , 130 and 131 , front contact 132 of the relay $1D$, wires 133 and 134 , winding of the relay $1E$, wires 135 and 54 , and then through elements 55 to 82 inclusive to the common return wire C . With the contacts of relay $1E$ picked up, it is stuck up through the following stick circuit:—

beginning at the terminal B front contact 136 of the relay 1E, wires 137 and 134, winding of the relay 1E, wires 135 and 54, elements 55 to 82, inclusive, to common return wire C.

5 With the relay 1E energized, alternating current, derived from the high frequency generator HFG, is superimposed on the line wire 1 thereby energizing the transfer relays TR¹ and TR² through the following circuit:—beginning at the generator HFG, wires 138 and 139, front contact 140 of the relay 1E, wire 141, to the line wire 1, inductance 142, condenser 143 winding of the alternating current transfer relay TR¹, line wire 1 between station No. 1 and station No. 2, inductance 144, condenser 145, winding of the relay TR² to common return wire C. Referring to the line relays LR² and TR², attention is directed to the fact that these relays are connected in multiple and are so designed that the alternating current will flow freely through the line relays TR¹ and TR², whereas the direct current will flow freely through the line relays LR¹ and LR², this because the inductance 144 and condenser 145 have such constants as to resonate the branch circuit including inductance 144, condenser 145 and relay TR² in series with the frequency of the generator HFG, the inductance of the line relay LR² being sufficient to suppress the flow of alternating current through said relay LR². However, direct current cannot flow through the condenser 145, so that the direct current will flow only through the line relay LR². With this circuit completed for the alternating current, relays TR¹ and TR² will assume their energized positions.

35 With the contact 99 of the relay TR² assuming its attracted position, the following pick-up circuit for the relay SR² is closed:—beginning at the terminal B, front contact 90 of the relay TR², wire 150, front contact 157 of relay SR¹, wires 152 and 153, winding of the relay SR², wires 154, 97, back contact 98 of the relay SR³, wires 99, 100 and 101, back contact 102 of the relays RSR². This relay RSR² remaining in its deenergized position, until the line relay LR² assumes one or the other extreme positions for an extra long period of time. Picking up of the station selecting relay SR² opens the stick circuit for the relay SR¹ at the back contact 95 of the relay SR² and closes its own stick circuit, which is traced as follows:—beginning at the terminal B, front contact 156, wire 153, winding of relay SR², wires 154 and 97, back contact 93 of relay SR³, wires 99, 100 and 101, back contact 102 of the relay RSR². With the station selecting relay SR² now energized station No. 2 is selected and the channel selecting relays A², B², C², D² and E² are rendered responsive to the changes in the position of the line relay LR², but since the line relay LR² still assumes its left hand position nothing further happens at this instant. However, as soon as the relay 1D becomes deenergized, positive potential is placed on the stepping wire 1, through front contact 30, in a similar manner as heretofore explained for preceding message channel selecting relays.

65 With the line relay LR⁰ assuming its right hand position the stepping relay 2A is energized through the following pick-up circuit:—beginning at the terminal B, contact 37 of relay LR⁰ assuming its right hand position, wires 105, 157 and 158, front contact 159 of the relay 1E, wires 160 and 161, winding of the relay 2A, wires 162 and 57 through elements 58 to 82, inclusive, to common return wire C. With the relay 2A assuming its energized condition the following stick circuit for said relay 2A is closed:—beginning at the terminal B, front

contact 163, wires 164 and 161, winding of the relay 2A, wires 162 and 57, and then through elements 58 and 82 inclusive, to common return wire C.

With the relay 2A energized, it closes its front contact 166, thereby shunting the contact 140 of the relay 1E and maintaining the alternating current applied to the stepping line in spite of opening of the contact 140, this relay 1E being deenergized in response to energization of the relay 2A by reason of opening of back contact 55 of relay 2A.

With line relay LR² assuming its right hand position and with the station selecting relay SR² energized the following pick-up circuit is closed for the channel selecting relay A² (the closure of this circuit being simultaneous with closure of the pick-up circuit for relay 2A just traced):—beginning at the terminal B of a suitable battery, front contact 166 of the relay SR², wire 167, polar contact 168 of the relay LR² assuming its right hand position, wires 169 and 170, back contact 171 of the relay B², wires 172 and 173, winding of the relay A², wire 174, back contact 175 of the relay B², wires 176 and 177, back contact 178 of the relay C², wires 179 and 180, back contact 181 of the relay D², wires 182 and 183, back contact 184 of the relay E², wires 185, 186 front contact 189 of the relay SR², wires 199 and 101, back contact 102 of the relay RSR² to common return wire C. With the relay A² now energized the following stick circuit therefore is closed:—beginning at the terminal B, front stick contact 187, of the relay A², wires 188 and 173, winding of the relay A², wire 174, contact 175, wires 176 and 177, contact 178, wires 179 and 180, contact 181, wires 182 and 183, contact 184, wires 186 front contact 189 of the relay SR², wires 199 and 101, back contact 102 of relay RSR² to common return wire C.

Also, with the relay 2A now energized, negative potential is applied to the stepping line through back contact 3 of relay CA⁰, wire 4, front contact 29 of relay 2A and back contacts 30, 31, 32, 33 and 34, of relays 1E, 1D, 1C, 1B and 1A respectively. This application of current of negative polarity to the stepping line causes the contacts of the line relays LR⁰, LR¹ and LR² to assume their left hand positions. The relays 2B and B² are now simultaneously energized through the following respective circuits:—(1) beginning at the terminal B, contact 37 of relay LR⁰ to the left, wires 38, 130, 190 and 191, front contact 192 of the relay 2A, wires 195, 196 and 197, winding of the relay 2B, wires 198 and 60, and through elements 61 to 82 inclusive, to common return wire C; and, (2) beginning at the terminal B, front contact 166 of the relay SR² (see Fig. 1C) wire 167, contact 168 of the relay LR² assuming its left hand position, wires 200 and 201, front contact 202 of the relay A², wires 203 and 204, winding of the relay B², wires 205 and 177, contact 178, wires 179 and 180, contact 181, wires 182 and 183, contact 184, wires 185 and 186, front contact 189, wires 199 and 101, back contact 102 to common return wire C. Also, with the relays 2B and B² now energized the following respective stick circuits are closed for these relays:—(1) beginning at the terminal B, front contact 207 of the relay 2B, wires 208 and 197, winding of the relay 2B, wires 198 and 60, and through elements 61 to 82 inclusive, to common return wire C; and (2) beginning at the terminal B, front contact 210 of the relay B², wires 211 75.

and 204, winding of the relay B², wires 205 and 177, contact 178, wires 179 and 180, contact 181, wires 182 and 183, contact 184, wires 185 and 186, front contact 189, wires 199 and 101, back contact 102, to common return wire C.

Energization of the stepping relay 2B again reverses the polarity of the potential applied to the stepping line by applying positive instead of negative potential to the stepping line wire 1 through the back contact 5 of relay CB⁰, wire 6, front contact 28 of relay 2B, and back contacts 29, 30, 31, 32, 33 and 34 of the relays 2A, 1E, 1D, 1C, 1B and 1A respectively.

This application of positive potential operates the line relays LR⁰, LR¹ and LR² to the right, whereby pick-up circuits for relays 2C and C², respectively, are closed as follows:—(1), beginning at the terminal B, contact 37 of line relays LR⁰ to the right, wires 185, 151, 220 and 221, front contact 222 of the relay 2B, wires 223, 226 and 227, winding of the relay 2C, wires 228 and 63, through elements 64 to 82 inclusive, to common return wire C; and, (2) beginning at the terminal B, contact 166 of station selecting relay SR², wire 167, contact 168 of the line relay LR² to the right, wires 169 and 170, front contact 171 of the relay B², wires 230 and 231, winding of the relay C², wires 233 and 180, back contact 181 of relay D², wires 182 and 183, back contact 184 of relay E², wires 185 and 186, front contact 189 of relay SR², wires 199 and 101, back contact 102 of relay RSR² to common return wire C.

With the relays 2C and C² picked up by the completion of the circuits just traced, the following stick circuits are closed for the relays 2C and C², respectively:—(1) beginning at the terminal B, front contact 235 of the relay 2C, wires 236 and 227, winding of the relay 2C, wires 228 and 63, elements 64 to 82 inclusive to common return wire C; and, (2) beginning at terminal B, front contact 237 of relay C², wires 238 and 231, winding of the relay C², wires 233 and 180, back contact 181, wires 182 and 183, back contact 184, wires 185 and 186, front contact 189 of relay SR², wires 199 and 101, back contact 102, to common return wire C. Picking up of the contacts of relay 2C by opening its back contact 61, de-energizes the relay 2B and similarly picking up of the relay C² by opening its back contact 178 de-energizes relay B². Also, closure of contact 241 of the relay 2C applies alternating current to the stepping circuit to maintain the transfer relays TR¹ and TR² energized in spite of deenergization of relay 2B and the opening of the alternating current circuit at the contact 240 of the relay 2B. Further, with the relay 2C energized and the relay 2B deenergized potential of negative polarity is applied to the stepping circuit through the front contact 27 of relay 2C and the back contact of all the preceding relays in the series of stepping relays.

With the negative potential applied to the line circuit, the line relays LR⁰, LR¹ and LR² assume their left hand positions and with the relays 2C and C² energized the following pick-up circuits are completed for the relays 2D and D², respectively:—(1) beginning at the terminal B, contact 37 of the line relay LR⁰ to the left, wires 38, 130, 190, 243 and 244, front contact 245 of the relay 2C, wires 246, 249 and 250, winding of the relay 2D, wires 251 and 66, and through elements 67 to 82 inclusive to common return wire C; and, (2) beginning at the terminal B (see Fig. 1C) front contact 166 of the relay SR², wire 167, con-

tact 168 of the relay LR² to the left, wires 209 and 252, front contact 253 of the relay C², wires 254 and 255, winding of the relay D², wires 256 and 183, back contact 184, wires 185 and 186, front contact 189 of relay SR², wires 199 and 101, back contact 102 of the reset relay RSR² to common return wire C.

With these relays 2D and D² energized the following respective stick circuits are closed for these relays:—(1) beginning at the terminal B, front contact 258 of the relay 2D, wires 259 and 250, winding of the relay 2D, wires 251 and 66, through elements 67 to 82 inclusive, to common return wire C; and, (2) beginning at the terminal B, front stick contact 260 of the relay D², wires 261 and 255, winding of the relay D², wires 256 and 183, back contact 184 of the relay E², wires 185 and 186, front contact 189 of relay SR², wires 199 and 101 back contact 102 to common return wire C. With these relays 2D and D² energized another distinctive and specific message circuit is completed as more clearly pointed out herein-after.

Energization of relays 2D and D² causes deenergization of the next preceding relays 2C and C² respectively, for reasons obvious from their stick circuits. Further, with the relay 2D now energized and relay 2C deenergized the alternating current for the stepping circuit flows through the contact 263 of the relay 2D instead of flowing through the contact 241 of the relay 2C. Further, with the relay 2D energized and 2C deenergized direct current of positive polarity is applied to the stepping circuit through the medium of back contact 16 of relay CD⁰, wire 17, front contact 26 of the relay 2D, and the back contacts 27, 28, 29, 30, 31, 32, 33 and 34 of the preceding stepping relays.

With current of positive polarity applied to the stepping circuit, the line relays LR⁰ and LR² will assume their right hand position thereby completing the following two, respective, pick-up circuits for the relays 2E and E²:—(1) beginning at the terminal B, contact 37 of the line relay LR⁰ assuming its right hand position, wires 105, 151, 220, 264 and 265, front contact 266 of the relay 2D, wires 267, 270 and 271, winding of the relay 2E, wires 272 and 69, through elements 70 to 82 inclusive, to common return wire C; and, (2) starting at the terminal B, front contact 166 of the relay SR² (see Fig. 1C) wire 167, contact 168 of the relay LR² assuming its right hand position, wires 169, 273 and 274, front contact 275 of relay D², wires 276 and 277, winding of the relay E², wires 278 and 186, front contact 189 of relay SR², wires 199 and 101, back contact 102 of the relay RSR², to common return wire C.

With the relays 2E and E² energized the following stick circuits, respectively, are closed for the relays 2E and E²:—(1) beginning at the terminal B, front stick contact 280 of the relay 2E, (see Fig. 1B) wires 281 and 271, winding of the relay 2E, wires 272 and 69, elements 70 to 82 inclusive, to common return wire C; and, (2) beginning at the terminal B, front contact 282 of the relay E², wires 283 and 277, winding of the relay 2E, wires 278 and 186, front contact 189 of the relay SR², wires 199 and 101, back contact 102 of relay RSR², to common return wire C, so that the relays 2E and E² are now stuck up. With these relays 2E and E² energized, the stick circuits for the relays 2D and D² are broken by the contacts 67 and 184, respectively, of the relays 2E and E².

With the relay 2E energized and the relay 2D 75

deenergized alternating current is cut off of the stepping line by opening of contact 263, the contact 284 of the relay not being connected up. The relays 2E and E² are energized simultaneously long enough to complete the desired message circuit, which message circuit will be more clearly described hereinafter.

With the alternating current cut off of the stepping circuit, the transfer relay TR² is deenergized thereby picking up the station selecting relay SR³ through the following pick-up circuit:—beginning at the terminal B, back contact 90 of the relay TR² (see Fig. 1C) wires 91 and 286, front contact 92 of the relay SR³, wires 287 and 288, winding of the relay SR³, wires 289, 100 and 101, back contact 102 of the relay RSR², to common return wire C. With this circuit completed the station selecting relay SR³ is energized, and is then stuck up through the following stick circuit:—beginning at the terminal B, back contact 90 of the relay TR², wires 91 and 290, front contact 291 of the relay SR³, wire 288, winding of the relay SR³, wires 289, 100 and 101, contact 102 of the relay RSR² to common return wire C. Picking up of the station selecting relay SR³ effects deenergization of the relay SR², because the stick circuit for this later relay is opened at the back contact 98 of the relay SR³.

Having now pointed out specifically how the stepping relays 2A, 2B, 2C, 2D and 2E are synchronously energized successively with the message channel selecting relays A², B², C², D² and E² at way station No. 2, it will now be pointed out how the simultaneous energization of corresponding relays completes specific message circuits, or message channels, being closed sequentially and each message channel including the same message wire 2. Further operations which occur during this first cycle of operation being described, will be set forth hereinafter.

OS indication scanning.—It will be reiterated here, that the normal operation of the system is to transfer the control of the dispatcher's office from one way station to the next way station successively, and to operate the message channel relays successively at each way station when that way station is under control. These sequential operations occur at a certain predetermined rate which allows the stepping relays at the dispatcher's office to be simultaneously energized with the corresponding message channel selecting relays at a way station, for a period of time long enough that a distinctive indication may be transmitted over the message channel thereby set up. As the sequential operation of the various message channel selecting relays has been pointed out, only the message channels thereby established will be specifically traced.

Let us first assume that a train is moving in an east bound direction over the main track of the passing siding PS, while this cycle of operation which is being described, and in so doing the track relay T is deenergized. With the track relay T deenergized negative current may flow from way station No. 2 to the indicating relay TI in the dispatcher's office through a message channel closed when the contacts of relays 2E and E² simultaneously assume the energized position.

The message channel established during each cycle of operation by the energization of relays 2E and E² is traced as follows:—beginning at the terminal (B—), through back contact 326 of the track relay T, wire 327, front contact 328 of the relay E², wire 239, back contact 330 of the

relay C², wire 333, back contact 334 of the relay B², wire 335, back contact 336 of the relay A², wire 337, message wire 2 to the dispatcher's office, wire 338, back contact 339 of the relay 2A, wire 340, back contact 341 of the relay 2B, wire 342, back contact 343 of the relay 2C, wire 344, back contact 345 of the relay 2D, wire 346, front contact 347 of the relay 2E, wire 348 winding of the relay TI, wire 349, to the common wire C. This application of current of negative polarity causes the contact 350 of the relay TI to be moved to the left thereby completing the energizing circuit for the indicating lamp TL, indicating to the dispatcher the presence of a train on the main track of the passing siding PS. Other similar message channels will be specifically pointed out hereinafter.

As the train approaches the signal S² it receives a stop indication. This is because the signal lever SCL is in its neutral position, which controls certain traffic controlling devices through the medium of local circuits, automatically set up by the use of an interruption or hesitation in the operation of the system during the selection of a particular message channel. In other words, the OS indication messages are transmitted over the message channel set aside for each OS indication by the application of positive or negative potential, while control indication messages are repeated according to whether a certain message channel is completed for a long or a short period of time. The normal operating period of time for a message channel is determined by the stepping relays 1A, 1B, 1C, etc., while the hesitation period is determined by the insertion of an extra time element accomplished by means of a hesitation relay. This hesitation which is repeated at the way station under control at the time of hesitation, completes certain local circuits which may be conveniently termed local hesitation repeater circuits.

Completion of local hesitation repeater circuits.—Attention is again directed to the hesitation relay HR² (see way station No. 2) and the slow-acting relay RSR². These relays are timed differently and the relay HR² will assume its energized condition after the line relay LR² assumes one particular extreme position for a reasonably long period of time, but the slow-acting reset relay RSR² does not assume its energized position unless the line relay LR² assumes one particular extreme position for an unusually long period of time. In this connection the reset relay RSR² is intended to respond during the period required for the stepping relay 3E to assume its energized position whereas the hesitating relay HR² is constructed to assume its energized position after a much shorter period of time such as allowed by the hesitating relays HA, HB, HC, HD and HS (see Fig. 1A).

Let us now see how and under what circumstances the hesitating relay HR assumes its energized position, bearing in mind that it assumes its deenergized condition during a cycle of operation where the successive steps are of the usual duration. If, on the other hand, the synchronous selector system is caused to hesitate at a particular step, as will be the case when the stepping relay 3A is energized in response to energization of the next preceding step relay 2E, the hesitating relay HR² will assume its energized position. In this connection, attention is directed to the fact, that the stop control relay ST⁰ (see Fig. 1B) is energized with the signal control lever SCL in its

neutral position. With the stepping relay E^2 now energized, as heretofore explained, and with the line relays LR^0 and LR^2 assuming their right hand positions in response to the positive potential applied to the stepping line by the fact that relay $2D$ was energized, an impulse of long duration is applied to the relay HS by reason of the fact that the hesitating relay HS must first be picked up and after this has been picked up a negative impulse will be placed on the stepping wire 1 to cause the next step to be taken. The energizing circuit for the relay HS may be traced as follows:—beginning at the terminal B , contact 37 of line relay LR^0 in its right hand position, wires 105 , 157 , 220 , 264 and 265 , front contact 266 of the relay $2D$, wires 267 and 219 , front contact 298 of the relay ST^0 , wire 299 , winding of the relay HS to common return wire C . After an interval of time due to the slow-acting characteristics of this relay HS , this relay HS will close its front contact 301 , thereby closing the circuit for placing negative potential on the stepping wire 1 , which circuit was opened at the back contact 18 of the relay ST^0 . The circuit for placing negative potential on the stepping line is traced as follows:—from the terminal $(B-)$, through front contact 300 of relay HS , wire 301 , front contact 18 , wire 19 , front contact 25 and through back contacts 26 , 27 , 28 , 29 , 30 , 31 , 32 , 33 and 34 to the stepping wire 1 . It is thus seen, that the contacts of the line relays remain in right hand positions during a long interval of time, due to the fact that the slow-acting relay HS is interposed between the relay $2E$ and the source of energy for placing negative potential on the stepping line wire 1 .

With the contact 165 of the line relay LR^2 in a right hand position for this long period of time the energization of the relay HR^2 is thereby effected, however the energization of the reset relay RSR^2 is not effected. Also, this occurs while the stepping relay $2E$ and the channel selecting relay E^2 are energized, and for this reason the following local hesitation repeater circuit for the stepping relay ST^2 (see Fig. 1C) is momentarily completed:—beginning at the terminal B , front contact 310 of the relay HR^2 , wire 311 , front contact 312 of the station selecting relay SR^2 , wire 313 , back contact 314 of the station selecting relay SR^1 , wire 315 , back contact 316 of the relay A^2 , wire 317 , back contact 318 of the relay B^2 , wire 319 , back contact 320 of the relay C^2 , wire 321 , back contact 322 of the relay D^2 , wire 323 , front contact 324 of the relay E^2 , wire 325 , winding of the relay ST^2 , to common return wire C . Momentary energization of the stop relay ST^2 momentarily applies current of negative polarity to each of the relays EM , WM , ES and WS , but since the relays already assume the left hand position, this being the normal position when all the signals are held at stop nothing will transpire at this time, the signal control lever SCL being in its middle neutral position. It is noted that the OS indication heretofore described, was transmitted before the relay HR^2 became energized, hence one indication is transmitted and one indication repeated during the time that relays $2E$ and E^2 are simultaneously energized.

To resume discussion of the operation of the system during the first cycle described, it will be stated that, the stepping relays $3A$, $3B$, $3C$, $3D$ and $3E$ are energized successively because of repeated reversals of polarity of potential applied to the stepping line wire 1 in a manner identical

to that pointed out for relays $2A$, $2B$, $2C$, $2D$ and $2E$, and it is believed unnecessary to specifically trace the circuits whereby these relays $3A$, $3B$, $3C$, $3D$ and $3E$ are successively picked up. It should, however, be noted that, when the relay $3E$ is becoming energized, this being a slow-acting relay, an exceptionally long impulse of negative polarity is applied to the stepping circuit, and this negative polarity is of sufficient time duration to pick up the contact 102 of the slow-acting relay RSR^2 . With the contact of each reset relay at each way station open, it is assured that all of the message channel selecting stick relays at each way station will be deenergized, these being in the stick circuit for each of these relays, and further opening of the contacts of the reset relays, such as 162 of relay RSR^2 , assures dropping of all the station selecting relays SR^1 , SR^2 , SR^3 , etc. at each way station since the stick circuits for these station selecting relays all pass through the back contact of the reset relay for a particular way station. In other words, the long impulse obtained by reason of the slow-acting stepping relay $3E$ effects resynchronization of the system, so that in the event that a foreign impulse such as a lightning discharge should get the relays out of step, these channel selecting relays and way station selecting relays will be resynchronized at the end of each cycle of operation, so that corresponding channel selecting relays will be energized simultaneously during the next following cycle of operation.

Referring now to Figs. 1A and 1B attention is directed to the fact that alternating current is not applied to the stepping line wire 1 , when either of the stepping relays $1A$, $1B$, $1C$ or $1D$ is energized, that such alternating current is applied to the stepping line wire 1 , while any of the stepping relays $1E$, $2A$, $2B$, $2C$ or $2D$ is energized, such alternating current is not applied while either of the relays $2E$, $3A$, $3B$, $3C$, $3D$ or $3E$ is energized. In other words, the alternate application and removal of alternating current potential upon the stepping circuit is the characteristic which transfers the control of the dispatcher from one way station to the next way station successively, which characteristic in order to carry out the transfer function is made effective one step before the first channel selecting relay of the next way station is to be energized. It is obvious from the drawings that this is accomplished by the energization of the last message channel selection relay of the way station selected preceding the way station next to be selected.

Let us now assume that the train moving in an eastwardly direction accepts the clear signal S^2 and treads upon the detector track circuit containing track relays DT , thereby deenergizing this track relay DT , and completing a message circuit, which controls the indicating relay DI in the dispatcher's office each time that the relays $2C$ and C^2 are energized. This message circuit with the track relay DT deenergized may be traced as follows:—beginning at the terminal $(B-)$, back contact 351 of the relay DT (see Fig. 1C), wire 352 , front contact 332 of the relay C^2 , wire 333 , back contact 334 of the relay B^2 , wire 335 , back contact 336 of relay A^2 , wire 337 , message wire 2 , wire 338 , (see Fig. 1A) back contact 339 of the relay $2A$, wire 340 , back contact 341 of the relay $2B$, wire 342 , front contact 343 of the relay $2C$, wire 353 , winding of the indicating relay DI , wire 354 , to common return wire C . This application of current of negative polarity to the

indicating relay DI causes the contact 355 to be moved to the left thereby illuminating the indicating lamp DL. The removal of the train from the track circuit will of course again extinguish the lamp DL for obvious reasons.

Dispatcher's control of traffic.—Let us now observe the operation in response to the dispatcher's desire to clear the east bound signal S² for the main track of the passing siding PS. At this time we will assume that the synchronous selector system is operating in a manner heretofore explained, so it will be merely stated that certain relays are energized simultaneously for certain periods of time.

Since the switch machine SM already assumes its main track position, as is indicated by the indicator lamp NL, the dispatcher will not need to move the switch machine lever SML. However, in order to set up east bound traffic, he will move the signal control lever SCL to the right thereby closing the following circuit for the control relay CA⁰ (see Fig. 1A):—beginning at the terminal B, signal control lever SCL to the right, wire 361, contact 362 controlled by the switch machine lever SML, wire 363, winding of the relay CA⁰ to common return wire C. The energization of the relay CA⁰ interposes a contact of the hesitating relay HA between the negative potential source and the contact of stepping relay 2A which applies negative potential to the stepping wire 1, and thus causes the message circuit associated therewith to be completed, while the relays 2A and A² are energized and also causes the hesitating relay HR² to be energized during this step, so that the following local hesitation repeater circuit for the control relay CA² is closed:—beginning at the terminal B, front contact 310 of the hesitating relay HR², wire 311, front contact 312 of the relay SR², wire 313, back contact 314 of the relay SR¹, wire 315, front contact 316 of the relay A², wire 365, winding of the relay CA² to common return wire C. Momentary completion of this energizing circuit for the relay CA² causes the contacts 366, 367, 368, and 369 of the relay CA² to be closed momentarily, thereby applying negative potential to each of the relays WM, ES and WS but since these relays already assume the left hand position they will not be effected thereby, but the contact 366 of relay CA² applies positive potential to the relay EM thereby permitting the wayside signal S² to assume a favorable traffic condition in accordance with traffic conditions in advance, this through the medium of the polar contact 370 of the relay EM. Likewise, if the switch machine SM has not already assumed the main track position, movement of the contact 371 to its right hand position would have operated the switch machine SM.

Let us now observe how the clearing of signal S² is manifested in the dispatcher's office. With the signal S² assuming its present clear position, this signal being assumed to be a two-position signal for convenience, the relay EI is energized (see Fig. 1C) for obvious reasons. With this signal indicating relay EI assuming its energized position, current of negative potential is applied to the stop indicating relay SI located in the dispatcher's office through the following message circuit:—beginning at the terminal (B—), front contact 372 of the relay EI, wire 373, back contact 374 of the relay WI, wire 375, front contact 330 of the relay D², wire 331, back contact 332 of the relay C², wire 333, back contact 334 of the relay B², wire 335, back contact 336 of the contact A², wire 337, message wire 2, wire 338,

(see Fig. 1A) back contact 339 of the relay 2A, wire 340, back contact 341 of the relay 2B, wire 342, back contact 343 of the relay 2C, wire 344, front contact 345 of the relay 2D, wire 377, winding of the stop indicating relay SI, wire 378, to common return wire C. Application of negative potential to the indicating relay SI, causes the stop light SL to be extinguished and causes the east bound traffic light EL to be energized through the following circuit:—beginning at the terminal B, polar contact 379, of the relay SI in its left hand position, wire 380, polar contact 381 of the relay EW in its right hand position, wire 382, indicating lamp EL to common return wire C.

Let us now observe certain other combinations of control without the use of a train for giving certain OS indications. This may be done by arbitrarily choosing the control to be described.

If the switch machine lever SML is now moved to the upper position with the signal control lever SCL in its right hand position, the following energizing circuit for the control relay CB⁰ is closed:—beginning at the terminal B, contact lever SCL in its right hand position, wire 361, contact 362 in its raised position, wire 383, winding of the relay CB⁰, to the common wire C. The contact 225 of the hesitating relay HB is now interposed between the source of negative potential and the contact 28 of the stepping relay 2B which places negative potential on the stepping wire 1, so that a hesitation will occur while the relays 2B and B² are energized, from which it appears that the hesitating relay HR² will assume its energized position while relay B² is energized thereby completing the following local hesitation repeater circuit for the control relay CB²:—beginning at the terminal B, front contact 310 of the relay HR², (see Fig. 1C) wire 311, front contact 312 of the relay SR², wire 313, back contact 314 of the relay SR¹, wire 315, back contact 316 of the relay A², wire 317, front contact 318 of the relay B², wire 384, winding of the control relay CB² to common return wire C. With the control relay CB² momentarily energized the contacts 385, 386, 387 and 388 momentarily apply negative potential to the relays EM, WM and WS, but the contact 386 momentarily applies positive potential to the relay ES, thus operating the relay ES to the right hand position to cause east bound traffic to be set up off of the siding. It will be noted, that movement of contact 389 of the relay ES to its right hand position applies current to the reverse wire of the switch machine SM, thereby operating this switch machine to the take-siding position. Also, it will be noted that the movement of contact 390 to its right hand position renders the dwarf starting signal S⁴ subject to automatic control, so that this signal S⁴ may assume its clear position, providing traffic conditions in advance are favorable.

Let us now observe how movement of the track switch from its normal main track position to its take-siding position will be manifested in the dispatcher's office. With this track switch on the east end of passing siding PS assuming its take-siding position current may flow from the terminal B, through the contact 357 in its lower position during the time of each cycle during which the relays 2A and A² are energized, this circuit being traced as follows:—beginning at the terminal (B—), switch box contact 357, wire 358, front contact 336 of the relay A², wire 337, message wire 2, wire 338 (see Fig. 1A) front contact 339 of the relay 2A, wire 359, winding of the indicating relay SMI, to common return wire C. This

application of current of negative polarity to the indicating relay SMI causes the indicating lamp RL to be energized informing the dispatcher that the switch machine is in its reverse position 5 and causes the normal indicating lamp NL to be extinguished, this through the medium of the polar contact 390 of the relay SMI.

Let us now see how movement of the signal control lever SCL to its extreme left hand position, with the switch machine lever SML in its lower position causes west bound traffic to be set up on the main track. With these levers in the positions just mentioned, the following circuit for the control relay CC⁰ is completed:—beginning at the terminal B, contact of the lever SCL in its left hand position, wire 391, contact 392 in a lower extreme position controlled by the left SML, wire 393, winding of the relay CC⁰, to common return wire C. With the relay CC⁰ energized the contact 247, the hesitating relay HC to be interposed between the contact 21 of the stepping relay 2C and the negative potential which it places on the stepping wire 1, thereby causing the step during which the relay 2C and 15 C² are energized to hesitate and thereby complete the following local hesitation repeater circuit for the control relay CC² (see Fig. 1C):—beginning at the terminal B, front contact 310 of the relay HR², wire 311, front contact 312 of the relay SR², wire 313, back contact 314 of the relay SR¹, wire 315, back contact 316, wire 317, back contact 318, wire 319, back contact 320, wire 321, front contact 322 of the relay D², wire 402, winding of the control relay CD², to the common wire C. With the relay CD² momentarily energized, and bearing in mind that the contacts of relays EM, ES and WS assume their left hand normal position but that the contacts of the relay WM assume their right hand position, the contact 405 of relay CD² when momentarily closed returns the contacts of relay WM back to their normal position, but the contact 406 of the relay CD² applies current of positive 20 polarity to the relay WS momentarily, thereby operating the contacts of relay WS to their right hand position. With the contacts of relay WS in their right hand position, the contact 407 of this relay WS applies current to the reverse wire of 25 the switch machine SM, thereby again operating the switch machine to the take-siding position, and the contact 408 of this relay WS applies current to the take-siding signal S³ thus informing the approaching train that it is to take the siding. 30

Referring again to the levers in Fig. 1A of the drawings, let us assume that the signal control lever SCL is in its left hand position to cause a west bound traffic condition to be established, and that the switch machine lever SML is operated to its raised dotted line position to cause side track conditions to be established. Under this condition of the levers SCL and SML, the following circuit for the control relay CD⁰ is closed:—beginning at the terminal B, lever contact SCL in its left hand position, wire 391, contact 392 of the lever SML in its raised position, wire 400, winding of the relay CD⁰ to common return wire C. With the control relay CD⁰ energized, the contact 401 of the hesitating relay HD is now interposed between the source of negative potential and the contact 26 of the stepping relay 2D which places negative potential on the stepping wire 1, whereby the slow-acting relay HD must assume its energized position before current is applied through the contact 401 of this relay to the stepping wire 1. The time consumed in the picking up the hesitating relay HD leaves the polar line relays LR¹, and LR² in the same position for a sufficient period of time to cause 45 the hesitating relay HR² to close its front con-

tact, although it transpires during the time that relays 2D and D² assume their energized position, so that the following local hesitation repeater circuit for the control relay CD² is momentarily closed:—beginning at the terminal B, front contact 310 of the relay HR², wire 311, front contact 312 of the relay SR², wire 313, back contact 316, wire 317, back contact 318, wire 319, back contact 320, wire 321, front contact 322 of the relay D², wire 402, winding of the control relay CD², to the common wire C. With the relay CD² momentarily energized, and bearing in mind that the contacts of relays EM, ES and WS assume their left hand normal position but that the contacts of the relay WM assume their right hand position, the contact 405 of relay CD² when momentarily closed returns the contacts of relay WM back to their normal position, but the contact 406 of the relay CD² applies current of positive 20 polarity to the relay WS momentarily, thereby operating the contacts of relay WS to their right hand position. With the contacts of relay WS in their right hand position, the contact 407 of this relay WS applies current to the reverse wire of 25 the switch machine SM, thereby again operating the switch machine to the take-siding position, and the contact 408 of this relay WS applies current to the take-siding signal S³ thus informing the approaching train that it is to take the siding. 30

If the levers SCL and SML are now again returned to their normal solid line position, the synchronous selector system is caused to hesitate while the relays 2E and E² are energized, thus causing the stepping relay ST² to be momentarily 35 energized all in a manner as heretofore described, and this momentary energization of the stop relay causes momentary closure of the contacts 410, 411, 412 and 413, and since momentary closure of these contacts applies negative potential to 40 each of the relays EM, ES, WM and WS, the contacts of these relays are returned to their left hand normal positions, thus leaving the switch machine in the last position to which it was operated and putting all of the signals S¹, S², S³ and 45 S⁴ to stop.

Summary.—Applicant has thus provided a system of train dispatching, in which a synchronous selector group of relays is used for selecting a particular way station out of a large number of way stations through the medium of the application of alternating current to a stepping circuit intermittently, and a series of channel selecting relays as provided at each of these way stations of which the channel selecting relays of a selected 55 way station may be energized sequentially by the application of alternate, negative, and positive impulses to the same stepping circuit, suitable means being provided for resynchronization of the relays with the stepping relays in the dispatcher's office if they should get out of step. 60

The system is so organized, that if a particular channel selecting relay of a way station is left in its energized position for more than a predetermined time, a specific control function is 65 carried out in that way station entirely by local circuits at such way stations. In this connection, attention is directed to the fact, that the combined result of the position of various levers for a particular way station in the dispatcher's office results in causing the stepping relays in the dispatcher's office to hesitate during a particular 70 step in the cycle of their operation, and this hesitation to suitable means at the way station causes a particular permanent magnet stick type relay 75

to be thereby operated to carry out the multiplicity of functions determined by the amount of levers in the dispatcher's office.

In other words, even though the dispatcher wants to operate the switch machine and wants to clear a particular signal, the synchronous selector system need hesitate at one particular step only in its operation to carry out this plurality of functions, and for this reason the expenditure of time has been economized in, by so combining the combination of lever positions into a signal control impulse. Attention is also directed to the fact, that if no lever is moved, the time required to complete a single cycle of operation of the synchronous selector system is that time required to scan all of the message channels, each of which is used for OS indicating purposes, there being no time lost, during which control of distant switch machines or signals is contemplated. If, on the other hand, the dispatcher moves a lever in the dispatcher's office the step during which a particular message channel is completed is made a little longer than the time ordinarily required to take such step, conveniently called hesitation, this hesitation resulting in the energization of a slow-acting relay at the way station.

The channel selecting relay is energized and thereby sets up a distinctive local hesitation repeater circuit for carrying out the particular desired control at such way station.

The system embodying the present invention is extremely flexible in that it may be extended from time to time by merely adding more relays, that the system is one that is comparatively simple in its manufacture in that it comprises a large number of duplicate units which may be manufactured in quantity, and that the system is readily adapted to various demands, in that any number of indications and controls may be afforded at a particular way station instead of the number specifically shown in the embodiment of the invention illustrated, and that the system is specially organized to economize in the time required for one complete cycle of operation to take place, bearing in mind that the minimum delay that may occur between the origination of an OS indication and its transmission through the system, is the time required for a complete cycle of operation to take place.

Having thus shown and described one rather specific embodiment of the present invention, and having shown rather specific circuit arrangements for carrying out the functions thereof, it is desired to be understood, that the particular circuit arrangement selected has been selected for the purpose of facilitating a disclosure of the invention rather than disclosing the scope of the invention or the particular circuit arrangement preferably used in carrying out the invention, and that various changes, modifications, and additions may be made to adapt the invention to the particular railway system to which it is to be applied, all without departing from the spirit or scope of the invention or the idea of means underlying the same, except as demanded by the scope of the following claims.

What I claim as new is:—

1. A train dispatching system of the synchronous selector type comprising, a stepping circuit, a message wire, alternating current responsive synchronous station selecting means operated solely by alternating current impulses transmitted over said stepping circuit, direct current responsive synchronous selector message circuit completing means operated by direct current im-
- 5 pulses transmitted over said stepping circuit only when rendered effective by said alternating current responsive synchronous station selecting means, and a plurality of message circuits each including said message wire and a contact of said message circuit completing means. 5
- 10 2. A train dispatching system of the synchronous selector type comprising, a stepping circuit, a message wire, alternating current responsive synchronous station selecting means operated by alternating current impulses transmitted over said stepping circuit, direct current responsive synchronous selector message circuit control means operated by direct current impulses transmitted over said stepping circuit only 15 when conditioned by said alternating current responsive synchronous station selecting means, a plurality of message circuits each including said message wire and a contact of said message circuit control means, and means for effecting a distinctive control of a traffic controlling device if a particular message circuit is closed for more than a predetermined time. 20
- 25 3. A train dispatching system of the synchronous selector type comprising; a stepping circuit including a plurality of electro-responsive units connected in series, each unit consisting of an alternating current relay, an inductance and a condenser connected in series together with a direct current relay connected in multiple therewith; one synchronous selector means for each electro-responsive unit operated solely by said alternating current relay of that unit; another synchronous selector means operated by said direction current relay; and a plurality of local channel circuits each including a contact of said one synchronous selector means and a contact of said another synchronous selector means in series. 30
- 35 4. A train dispatching system of the synchronous selector type comprising; a stepping circuit including a plurality of electro-responsive units connected in series, each unit consisting of an alternating current relay, an inductance and a condenser connected in series, together with a direct current polar relay connected in multiple therewith; one synchronous selector means for each of said units operated solely by said alternating current relay of that unit; another synchronous selector means for each of said units operated solely by said alternating current relay of that unit; another synchronous selector means for each of said units operated by said direct current polar relay when conditioned by said one synchronous selector means; a message wire; and a plurality of message circuits each including said message wire and a contact of said another synchronous selector means in series. 40
- 45 5. A train dispatching system of the synchronous selector type comprising; a stepping circuit including a plurality of electro-responsive units connected in series, each unit consisting of an alternating current relay, an inductance and a condenser connected in series, and a direct current relay connected in multiple therewith; one synchronous selector means operated by said alternating current relay; another synchronous selector means operated by said direct current relay when selected by said one synchronous selector means; a message wire; a plurality of message circuits each including said message wire and a contact of said another synchronous selector means in series; and means for effecting a distinctive control of a traffic controlling device in response to a hesitation in the operation of said another synchronous selector means. 50
- 55 6. In a train dispatching system of the syn-
- 60 70 75

chronous selector type; the combination with a plurality of stepping relays connected in a circuit arrangement so that the application of electrical energy will cause said relays to be picked up and dropped successively one at a time at a uniform stepping rate to complete cycles of operation, of means for at times causing a hesitation in the stepping rate at a particular step in a cycle of operation comprising; a slow-acting 5 hesitating relay, and means for at times inserting said hesitating relay between two successive stepping relays in their circuit connections, so that the additional time during which a particular stepping relay is energized is increased 10 to an extent corresponding to the difference between the time required for the hesitating relay and the stepping relay to assume their energized positions.

7. In a train dispatching system of the synchronous selector type; the combination with a plurality of stepping relays connected in a circuit arrangement so that the application of electrical energy will cause said relays to be picked up and dropped successively one at a time at a uniform stepping rate, of means for at times causing a hesitation in the stepping rate at a particular step in the cycle of operation comprising, a line relay, a circuit for controlling said line relay including a front contact of a particular stepping relay, said line relay when operated in response to closure of said circuit energizing the next succeeding stepping relay, a slow-acting hesitation relay, and means for including a front contact of said hesitation relay in series with said front contact of said particular stepping relay in said circuit.

8. In a train dispatching system of the synchronous selector type; the combination with a plurality of stepping relays connected in a circuit arrangement so that the application of electrical energy thereto will cause said relays to be picked up and dropped successively one at a time at a uniform stepping rate, of means for at times causing a hesitation in the stepping rate at a particular step in the cycle of operation comprising; a line relay, a circuit for controlling said line relay including a front contact of a particular stepping relay, said line relay when operated in response to closure of said circuit energizing the next succeeding stepping relay, a slow-acting hesitation relay, and means for simultaneously connecting said hesitation relay in multiple with said particular stepping relay and including a front contact of said hesitation relay in series with said front contact of said particular stepping relay in said circuit.

9. A train dispatching system of the synchronous selector type comprising; a stepping circuit; a message wire; alternating current responsive synchronous station selecting means operated solely by alternating current impulses transmitted over said stepping circuit; direct current responsive synchronous selector message circuit control means operated by direct current impulses transmitted over said stepping circuit; a plurality of message circuits each including said message wire and a contact of said message circuit control means; and means for resynchronizing said synchronous station selecting means and said synchronous message circuit control means at the end of each cycle.

10. A train dispatching system of the synchronous selector type comprising; a stepping circuit; a message wire, alternating current responsive synchronous station selecting means operated by

alternating current impulses transmitted over said stepping circuit; direct current responsive synchronous selector message circuit control means operated by direct current impulses transmitted over said stepping circuit; a plurality of message circuits each including said message wire and a contact of said message circuit control means; means for effecting a distinctive control of a traffic controlling device if a particular message circuit is closed for more than a predetermined time; and means for resynchronizing said synchronous station selecting means and said synchronous message circuit control means at the end of each cycle. 5 10

11. In a selector system for controlling distant track switches and signals on a railroad, the combination with a plurality of way stations and a central office, of a line circuit connecting each of said way stations and said central office, selector apparatus located at each of said way stations 20 each selectively responsive to energize a particular relay in accordance with the number of impulses of each of two distinctive characters applied to said line circuit, and means at said central office for selectively applying different numbers 25 of current impulses of two distinctive characters to said line circuit, whereby said selector apparatus at any way station may be controlled from said central office.

12. In a selector system for controlling distant track switches and signals on a railroad, the combination with a plurality of way stations and a central office, of a line circuit connecting each of said way stations and said central office, selector apparatus located at each of said way stations 25 each responsive to energize a particular relay in accordance with the number of impulses of each of two distinctive currents applied to said line circuit, and in accordance with the duration of application of one of said impulses, means at said 40 central office for applying current impulses of two distinctive currents to said line circuit, and means for at times extending the duration of one of said impulses.

13. In a centralized traffic controlling system 45 for railroads, the combination with a central office and a plurality of way stations, of a stepping circuit and a message circuit connecting said central office and said way stations, station selecting means and code responsive means at each of said 50 way stations controlled entirely through the medium of said stepping circuit, traffic controlling devices at each way station, means at said central office for controlling the traffic controlling devices at a particular way station over the stepping circuit through the medium of the station selecting means and the code responsive means at that station; and means for simultaneously indicating in said central office the operated conditions of said traffic controlling devices at said 55 particular way station over said message circuit.

14. A code impulse generating relay group comprising, a series of stepping relays, a stepping line over which codes of impulses of various spaced durations are to be transmitted, a line relay in 65 said stepping line controlled by said stepping relays and for controlling said stepping relays, and an auxiliary slow-acting relay at times inserted to repeat a particular stepping relay and thereby delay the control of said line relay by said particular stepping relay so as to extend the time between successive impulses. 70

15. A code impulse generating relay group comprising, a series of stepping relays, a stepping line over which codes of impulses of various 75

- spaced durations are to be transmitted, a line relay in said stepping line controlled by said stepping relays and for controlling said stepping relays, and an auxiliary slow-acting relay at times inserted to repeat a particular stepping relay and thereby delay the control of said line relay by said particular stepping relay so as to extend the time between successive impulses.
16. In a system for controlling traffic on railroads, the combination with a dispatcher's office and a plurality of way stations, a stepping circuit and a message circuit connecting said dispatcher's office and said several stations, stepping relays in the dispatcher's office and at each station operated synchronously by impulses applied to said stepping circuit, station selecting means and code responsive means at each station including said stepping relays and responsive to the characteristics of the impulses applied to said stepping circuit, said code responsive means at a given station being responsive to the impulses applied to the stepping circuit only when the station selecting means at that station is operated, traffic controlling devices at each station governed by the code responsive means at that station, and means including said stepping relays for simultaneously transmitting indications from a selected station to the dispatcher's office over said message circuit.
17. In a system for transmitting controls from a dispatcher's office to several way stations and receiving indications in the dispatcher's office of the operated condition of traffic controlling devices at said stations, a stepping circuit and a message circuit connecting the dispatcher's office with the several stations, means acting over said stepping circuit alone for selecting said stations one at a time and for transmitting the desired controls to the selected station, and means for simultaneously communicating indications from said selected station to the dispatcher's office over said message circuit.
18. In a system of communication between a dispatcher's office and a plurality of way stations, a control line circuit and an indication line circuit connecting the dispatcher's office with the several stations, station selecting means and traffic controlling devices at each station governed over said control circuit alone, and indicating means in the dispatcher's office simultaneously governed over said indication line circuit.
19. In a dispatching system for railroads, a dispatcher's office, a plurality of way stations, a line circuit connecting said dispatcher's office with the several stations, means in the dispatcher's office for applying to said line circuit a plurality of alternating current impulses and a plurality of direct current impulses, and station selecting means and code responsive control means at each station actuated respectively by said impulses.
20. In a centralized traffic control system for railroads, a dispatcher's office and a plurality of way stations, a line circuit connecting said dispatcher's office with the several way stations, means in the dispatcher's office for applying to said line circuit a plurality of current impulses each impulse being one or the other of two distinctive characters, station selecting means at each way station responsive during a particular impulse of one character, and control means at each way station distinctively responsive to the duration of a particular impulse of the opposite character.
21. In a centralized traffic control system for railroads, a dispatcher's office and a plurality of way stations, a line circuit connecting said dispatcher's office with said way stations, means placing a plurality of impulses on said line circuit, means for selecting said stations successively said means selecting one station upon the application of each impulse and one station upon the removal of each impulse, and means governing traffic controlling devices over said line circuit at the selected station.
22. In a centralized traffic control system for railroads, a dispatcher's office and a way station, a plurality of control levers at said dispatcher's office, a track switch and signals governing traffic thereover at said way station, a stick relay for governing each route over said track switch, step-by-step means at the dispatcher's office and at the way station operated synchronously, a circuit connecting said dispatcher's office with said way station, a bank of code responsive relays at the way station governed in accordance with the position of said levers by impulses placed on said line circuit, and means including said code responsive relays for controlling all of said stick relays simultaneously.
23. In a centralized traffic controlling system for railroads, a dispatcher's office, a plurality of way stations, a single line circuit extending from said dispatcher's office through said way stations, means in the dispatcher's office for applying a series of impulses to said line circuit for selecting said stations selectively and transmitting controls to the selected station, said controls being transmitted by prolonging a particular impulse of the series applied while a particular station is selected, station selecting means at each station responsive to certain impulses of each series, and control means at each station responsive to a prolonged impulse of the series when the corresponding series of the station is selected.
24. In a centralized traffic controlling system for railroads; a line circuit; means for applying different series of impulses to said line circuit, each of said different series being distinctive by reason of the prolonged duration of a particular impulse of that series; step-by-step means operated one step for each impulse of a series; a plurality of stick relays; and means for distinctively controlling said plurality of stick relays simultaneously depending upon which impulse of the series is prolonged.
25. In a centralized traffic controlling system for railroads; a dispatcher's office; a way station, a plurality of control levers at said dispatcher's office; a track switch and signals governing traffic thereover at said way station; a line circuit connecting said dispatcher's office with said way station; means in the dispatcher's office for impressing on said line circuit a code made up of a predetermined number of code elements; means for selectively prolonging at least one of the code elements of a code in accordance with the position of said control levers; step-by-step means; means responsive to said code for operating said step-by-step means successively; a plurality of stick relays, each of said stick relays being adapted to govern a particular route over said track switch; and means for selectively controlling said stick relays simultaneously in accordance with the position of said step-by-step means when a prolonged code element occurs.

OSCAR H. DICKE.

DISCLAIMER

1,997,543.—*Oscar H. Dicke*, Rochester, N. Y. TRAIN DISPATCHING SYSTEM FOR RAILROADS. Patent dated April 9, 1935. Disclaimer filed February 8, 1937, by the assignee, *General Railway Signal Company*.

Hereby enters this disclaimer by disclaiming from claims 23 and 24 any system, except wherein the "impulses" specified are energizations of the "line circuit" and the "prolonged" impulse is a prolonged energization of said "line circuit".
